Inventor:

Robert Meyer
by his Atty's:

Philip Lazar Lees & Kennedy

UNITED STATES PATENT OFFICE.

ROBERT MEYER, OF MULHEIM-RUHR, GERMANY, ASSIGNOR, BY MESNE ASSIGNMENTS, TO WORTHINGTON PUMP AND MACHINERY CORPORATION, OF NEW YORK, N. Y., A CORPORATION OF VIRGINIA.

AUTOMATIC PLATE-VALVE.

1,341,145.

Specification of Letters Patent.

Patented May 25, 1920.

Application filed July 20, 1915. Serial No. 40,857.

To all whom it may concern:

Be it known that I, ROBERT MEYER, a subject of the German Emperor, residing at Mulheim-Ruhr, Germany, have invented 5 certain new and useful Improvements in Automatic Plate-Valves, fully described and represented in the following specification and the accompanying drawings, forming a part of the same.

10 This invention relates to automatic plate valves of that class described in my United States Letters Patent Reissue No. 13,991, dated October 12, 1915, the special object of 15 the invention being to provide an improved valve of this class, in which the valve shall be properly held in position and guided in its opening and closing movements, without any recesses for the valve in the valve seat, thus permitting the valve seat to be formed 20 and finished as a plain surface.

For a full understanding of the invention a detailed description of a construction embodying the invention in a preferred form will now be given in connection with the accompanying drawings, forming a part of 25 this specification, and the features forming the invention then specifically pointed out in the claims.

In the drawings:

30 Figure 1 is a longitudinal section of the valve with a portion of the cap broken away to show one of the ports in the cap.

Fig. 2 is a section on the line 2—2 of Figs. 1 and 3.

35 Fig. 3 is a plan of Fig. 1 with the valve seat partly broken away to show the construction.

Fig. 4 is a view similar to Fig. 1, with the valve open.

Referring to the drawings, A is the valve seat, shown as of circular form and having the series of straight ports *a*, each of which is controlled by the plate valve B, which opens against the cap or abutment C, the latter being shown as having a series of ports *b* out of line with the valve.

Valves B are held in position and guided without recesses or projections on the valve seat A, the latter thus being formed and finished as a plain surface co-acting with the valves in their closed position. The valves are held in position sidewise and guided in their opening and closing movements as follows: Recesses 1 in the cap receive the ends

of the valves, these recesses having inclined 55 or curved walls on the side toward which the valves open, so as to permit the latter to bend freely in the opening movement, and the side walls 2 of the recesses act to hold the valves in position sidewise in line with 60 the ports *a*.

The abutment surface of the cap between the recesses 1 is shown as formed straight for convenience of manufacture, the open valve bearing against it only over a portion 65 of its surface, but it will be understood that this is not essential, and this abutment surface may be curved and the open valve bear against it throughout.

The operation of the construction will be 70 clear from the drawings without extended description, it being understood that the valves B lie flat upon the valve seat A below the ports *a* in normal position, as shown in Figs. 1 to 3, and bend downward in opening 75 to the position shown in Fig. 4, their opening movement being limited by the abutment surface of cap C, and that the valves are held in position and guided in their opening and closing movements by the 80 walls of the recesses 1.

It will be understood that the invention may be embodied in other constructions than that shown, many modifications being possible without departing from the invention 85 as defined by the claims.

What I claim is:

1. The combination of a valve seat having one or more ports, one or more thin elastic plates forming valves and having both ends 90 free to permit bending of the entire valve in opening, and a cap provided with means at opposite ends of the valve for holding the valve in position and permitting the bending movement, said valve seat being 95 formed without recesses for the valve.

2. The combination of a valve seat having one or more ports, one or more thin elastic plates forming valves and having both ends 100 free to permit bending of the entire valve in opening, and a cap provided with recesses receiving the ends of the valve and curved or inclined to permit the bending of the valve, said valve seat being formed without recesses for the valve.

3. The combination of a valve seat having one or more ports, one or more thin elastic plates forming valves and having both ends 105

- free to permit bending of the entire valve in opening, and a cap provided with recesses receiving the ends of the valve and curved or inclined to permit the bending of the valve, said valve seat being formed without recesses for the valve, and means for holding the valve in position sidewise.
4. A valve seat having a plain surface, an elongated valve of elastic flexible material, and a cap having a concave recess, the said valve extending across the concave recess and at both ends loosely received between the ends of said recess and said seat.
5. A valve seat having a plain surface, an elongated valve of elastic flexible material, and a cap having a concave recess, the said valve being received between the ends of said recess and said seat and extending longitudinally across the concave recess, and

there being a clearance between said valve and the bottom faces of the ends of said recess when said valve is in normal closed position.

6. A valve seat having a plain surface with one or more ports, one or more thin elastic plates forming valves and having both ends free to permit bending of the entire valve in opening, and means at opposite ends of the valve for holding the valve in position and permitting the bending movement.

In testimony whereof, I have hereunto set my hand, in the presence of two subscribing witnesses.

ROBERT MEYER. [L. S.]
